UNITED STATES PATENT OFFICE.

CHARLES E. HOWE, OF NEW YORK, N. Y., ASSIGNOR TO SWEET, ORR & COMPANY, OF NEW YORK, N. Y.

DESIGN FOR FABRIC.

SPECIFICATION forming part of Design No. 36,141, dated November 11, 1902.

Application filed October 9, 1902. Serial No. 126,639. Term of patent 14 years.

To all whom it may concern:

Be it known that I, CHARLES E. HOWE, a citizen of the United States, and a resident of the city of New York, borough of Brooklyn, 5 in the county of Kings and State of New York, have invented and produced a new, original, and ornamental Design for a Fabric, of which the following is a full, clear, and exact description.

Reference is to be had to the accompanying drawing, forming a part of this specification, in which the figure is a plan view of a fabric design embodying my invention.

My design for a fabric consists of the representation of a series of railway-rails, and arranged at various points between pairs of rails and in inclined relation thereto are representations of locomotive-engines, and also at various points are representations of oil-caus, wrenches, and hammers, the handles of 20 the wrench and the hammer of a set being crossed and the oil-can arranged adjacent thereto.

Having thus described my invention, I claim as new and desire to secure by Letters 25 Patent—

The ornamental design for a fabric as herein shown and described.

In testimony whereof I have signed my name to this specification in the presence of 30 two subscribing witnesses.

CHARLES E. HOWE.
